BERNARD MACDONALD, OF LOS ANGELES, CALIFORNIA.

APPARATUS FOR SEPARATING MINERALS BY FLOTATION.

1,134,690.

Specification of Letters Patent.

Patented Apr. 6, 1915.

Application filed October 9, 1914. Serial No. 865,786.

To all whom it may concern:

Be it known that I, BERNARD MACDONALD, a citizen of the United States, residing in the city of Los Angeles, county of Los Angeles, and State of California, have invented certain new and useful Improvements in Apparatus for Separating Minerals by Flotation; and I do hereby declare the following to be a full, clear, and exact 10 description of the invention, such as will enable others skilled in the art to which it appertains to make and use the same.

This invention is directed to the provision of an improved form of apparatus for 15 the separation of floatable minerals from the rock or gangue with which they occur in association.

The practice of the invention involves a 20 preliminary crushing or grinding of the material to be treated and its mixture with water until it becomes a freely flowing pulp. In this condition, the pulp is conducted to a receptacle constructed in accordance with the invention and is mixed with the usual 25 emulsion of air, acid, oil and water whereby the mineral particles are entrapped and caused to rise to the surface of the pulp charge from which they may be skimmed off for subsequent treatment.

30 One feature of the invention resides in the provision of one or more upright transfer-pipes within the receptacle for the pulp through which the pulp is caused to rise vertically by means of compressed air, these 35 pipes having their outlets below the surface of the pulp so that the latter and the compressed air rising within the pipes are discharged into the mass undergoing treatment below its surface. In this way, new 40 supplies of the pulp are carried from the lower portion of the receptacle up into the region of the oily emulsion and are introduced therein along with substantial quantities of oil and compressed air which are 45 broken up into a multiplicity of small bubbles by contact with the pulp mass. This 50 practically continuous transfer of new pulp, air and oil from the bottom of the receptacle and the spouting of it into the upper frothy portion of the pulp charge creates the viscous emulsion of small oil-coated air-bubbles which entrap the mineral particles in the pulp and float them to the surface so 55 they may be skimmed off.

55 The outlets from the transfer pipes lo-

cated a short distance below the surface of the flotation liquid are preferably disposed circumferentially so that the pulp within the receptacle is caused to take up a circular motion within the receptacle. This permits 60 of readily skimming off the froth upon the surface of the flotation liquid by the provision of a guide or diverting board which directs the froth over a skimming board and into a suitable launder. Also, the outlets 65 from the transfer-pipes are preferably elongated horizontally so that the air and material issuing therefrom take the form of a wide thin sheet. This assists in breaking 70 up the air into a multiplicity of small bubbles and in mixing the air and sulfid particles with the oily material in the upper portion of the receptacle.

Another feature of the invention resides 75 in the provision of a receptacle for the pulp of annular form and means for causing the liquid to flow in a circular direction around this receptacle. Preferably, a cylindrical tank is employed as the receptacle for the 80 pulp and a circular diaphragm is mounted within the upper portion of this receptacle and concentric therewith. This forms between the diaphragm and the wall of the receptacle an annular space around which the frothy emulsion may be caused to flow until it comes to the skimmer over which the 85 froth is carried off to the launder. Preferably, the circular diaphragm is open at its lower end so that the pulp rises within it, but it is of sufficient depth to retain the 90 oily emulsion in the annular space between it and the wall of the receptacle.

Another feature of the invention resides 95 in the provision of means for introducing oil and such other material as may be found desirable along with the compressed air into the lower ends of the transfer-pipes so that the oil and pulp are pumped upwardly by the air and the oil, pulp and compressed air are discharged together into the upper portion 100 of the receptacle, thereby becoming intimately mixed with each other. In this way, the pulp is brought into more intimate mixture with the oily froth which entraps and carries to the surface the valuable minerals, while the gangue or rocky material of the pulp, for which the oily froth has no affinity, becomes separated from the valuable minerals and sinks through the pulp 105 mass to the bottom of the receptacle.

110

I have illustrated the preferred embodiment of my invention in the accompanying drawings, in which—

Figure 1, is a top view of the apparatus; Fig. 2 is a vertical section of the flotation receptacle, the oil and air connections thereto being shown diagrammatically, and Fig. 3 is a perspective view of the devices by which the frothy material is skimmed off.

10 Referring to these drawings, the apparatus comprises a cylindrical tank 4 for the pulp. Mounted within the upper end of this receptacle concentric therewith is a cylindrical diaphragm 5, preferably open at both ends and forming between it and the surrounding wall of the tank 4 an annular space within which the oily emulsion is adapted to move circumferentially. Within the receptacle are a plurality of transfer-pipes 6 mounted vertically within their lower intake ends a short distance above the bottom of the receptacle 4. These pipes 6 receive the pulp in the tank at their lower ends and this pulp is forced upwardly 20 through the pipes by compressed air. This air is admitted to the lower ends of the pipes 6 through compressed air pipes 7 extending upwardly through the bottom of the tank and having their upper ends projecting 25 within the lower, open ends of the transfer-pipes 6. At the upper ends of the transfer-pipes 6 are discharge outlets 8 which are directed circumferentially. Each of the outlet members 8 has an orifice which is in 30 the form of a horizontally elongated slot so that the material issuing from the upper end of the transfer-pipe is in the form of a wide thin sheet. By reason of the circumferential arrangement of the outlets at the upper 35 ends of the pipes 6, the material within the receptacle 4 and particularly the portion of the material within the annular chamber between the diaphragm 5 and the wall of the receptacle 4 is caused to take up a circular movement within the tank. As the 40 material moves thus, a froth is formed thereon by the agitation of the material discharged from the pipes and the admixture of oil and air therewith, and this froth rises 45 to the surface of the pulp and is carried around the tank in the annular space outside the diaphragm 5. At one or more points around the upper edge of the wall 50 of receptacle 4, that wall is cut away as shown in Fig. 3 so as to form a skimmer over which the frothy material at the surface of the pulp may pass into a launder 10 by which it is carried to the apparatus for 55 effecting the further treatment of the minerals carried by the froth. To assist in effecting the passage of the froth over the skimmer, a deflector or diverting board 11 is placed in position upon the diaphragm 5 and the wall of the receptacle at an incline 60 to the direction of the travel of the material 65

as shown in Figs. 1 and 3 so that this deflector 11 causes the froth to pass from the receptacle into the launder 10. In order to provide for adjustment of the height of the skimmer, a board separate from the wall of the receptacle is preferably employed. This board is shown at 21 in Fig. 3. It is laid against the inner side of the wall of the receptacle as shown and is sustained in position by bolts 22 depending from a bar 20 secured to the upper edge of the receptacle. By turning the nuts 19 on the bolts 23, the height of the board 21 may be regulated as desired.

It will be noted by reference to Fig. 2 that the discharge outlets of the transfer-pipes 6 are located below the level of the flotation liquid in the receptacle 4, this level being established by the position of the skimmer 21 over which the oily froth with the entrapped minerals flows into the launder 10. Because of this, the air, oil and pulp to be treated issue from the transfer-pipes into the body of the pulp within the receptacle. The resistance which the mass of the pulp in the receptacle offers to the portion spouted from the transfer-pipes aids materially in the formation of the viscous emulsion of small oil-coated air-bubbles which is desirable for the flotation of the mineral particles.

The bottom of the receptacle 4 preferably has a conical shape as shown at 12. This cone upon the bottom of the receptacle serves to divert thicker portions of the pulp within the receptacle toward the intake ends of the transfer-pipes so that they may be carried upwardly through the pipes and again subjected to the flotation effect of the emulsion in the upper portion of the receptacle.

The introduction of compressed air into the lower ends of the pipes 6 through the air supply pipes 7 causes the pulp to be raised within the pipes 6 in a plurality of layers separated by disks or pistons of compressed air as disclosed in my Patent No. 1,071,447 granted August 26, 1913. I have found it highly desirable to provide for the admission of the oil and other materials required for the flotation emulsion through the pipes 7 which carry the compressed air to the transfer-pipes 6. In Fig. 2, the pipes 7 are shown as connected to a pipe 13 leading from a source of supply of compressed air. A receptacle 14 for the oil employed in producing the emulsion is also connected to the pipe 13 by a pipe 15 in which is a valve 16. By opening the valve 16, oil may be introduced from the receptacle 14 into the pipes 13 and 7 so that it will be carried along with the compressed air flowing through those pipes into and through the transfer-pipes 6 to the flotation liquid within the receptacle 4. Any suitable means,

such as a pump, may be provided for effecting the flow of the oil from the receptacle 14. In Fig. 2, I have shown a pipe 17 connecting the upper portion of receptacle 14 with the air supply pipe 13 so that the oil within the receptacle 14 may be subjected to pressure. In the pipe 17 is a valve 18 whereby the flow may be regulated as desired so as to cause the introduction of the desired amount of oil into the pulp. By this provision for the introduction of the oil and other materials required for the flotation emulsion, these materials may be readily introduced in such quantities as may be found desirable for the 15 production of the emulsion best suited for the material being treated. Also, the admission of the oil along with the air facilitates the production of the emulsion by the formation of a multiplicity of small oil-coated air-bubbles from the compressed air issuing from the outlets of the transfer-pipes.

The material within the diaphragm 5 does not partake of the circular motion given to 25 the material outside the diaphragm to any substantial extent. Therefore, the solid constituents of the material within the diaphragm settle to the bottom leaving clear water within the diaphragm. This water 30 being of lower specific gravity than the pulp, rises to a level slightly higher than the level of the pulp in the annular space between the diaphragm 5 and wall 4. I utilize this water at the higher level to assist 35 in carrying the froth over the skimmer 21. For this purpose, a plurality of holes 9 are provided in the wall of the diaphragm 5 opposite the skimmer 21 through which small 40 streams of water pass radially from within the diaphragm and these streams aid in effecting the radial movement of the froth to 45 and over the skimmer.

For the introduction of the pulp into the receptacle 4, a conduit is provided whose 45 outlet is a substantial distance below the surface of the material in the receptacle. Such a conduit is shown at 23. A pipe 24 may be connected to this conduit to convey acid thereto. With the apparatus thus 50 constructed, the pulp material is delivered into the tank at a considerable distance below the surface; it then settles to the lower portion of the tank where it is taken up by the transfer-pipes, pumped to the surface of the pulp 55 material and mixed with the oil and air.

In the operation of the apparatus, the tank or receptacle 4 is filled with the material to be treated so that the surface of the material is close to the edge of the skimmer separating 60 the launder 10 from the interior of the receptacle. Compressed air is then admitted through the pipes 13 and 7 to the lower ends of the transfer-pipes 6 and serves to draw the pulp at the bottom of the tank 4 into the 65 lower ends of the transfer-pipes and carry

it upwardly to the upper portion of the tank where it is discharged circumferentially into the annular space between the cylindrical diaphragm 5 and the wall of the receptacle 4. The material discharged through the outlets of the transfer-pipes is given the form of a thin sheet so that the air is broken up 70 into a multiplicity of small bubbles. The discharge of air along with the pulp into the material within the receptacle 4 below 75 the surface of that material assists in the formation of the desirable emulsion and the intimate admixture of the pulp therewith and a froth appears upon the surface of the material in which the mineral particles are 80 floated. This froth partakes of the circular motion of the pulp caused by the circumferential discharge from the transfer-pipes 85 6 and passes around in the annular space between the diaphragm 5 and the wall of the receptacle until it comes into contact with the deflector 11 by which the froth is caused to pass over the skimmer and into the launder 10.

What I claim is:

1. Apparatus for separating metal minerals by flotation from associated gangue or rock comprising the combination of a receptacle, a transfer-pipe therein having a lower open intake end terminating within 90 the lower portion of the receptacle and an upper discharge end, means for effecting the flow of the material in the receptacle upwardly through the transfer-pipe, a launder and a wall over which the surface material in the receptacle passes from the receptacle to the launder, the outlet from said pipe being located below the surface of the material in the receptacle and directed laterally so that the material issuing therefrom will 95 cause movement of the material in the receptacle in a direction to carry the froth upon the material to said wall, substantially 100 as described.

2. Apparatus for separating metal minerals by flotation from associated gangue or rock comprising the combination of a receptacle, a plurality of vertically disposed transfer-pipes therein having lower open intake ends and upper discharge ends directed 110 horizontally and substantially parallel to the wall of the receptacle, means for admitting compressed air to the lower ends of the transfer-pipes to effect the flow of the material in the receptacle upwardly through the transfer-pipes, a launder and a wall over 115 which the surface material in the receptacle passes from the receptacle to the launder, which wall is located above the upper discharge ends of the transfer-pipes, substantially 120 as described.

3. Apparatus for separating metal minerals by flotation from associated gangue or rock comprising the combination of a receptacle, a vertically disposed transfer-pipe 125

therein having a lower open intake end terminating within the lower portion of the receptacle and an upper discharge end having an elongated discharge outlet which is 5 directed laterally, means for effecting the flow of the material in the receptacle upwardly through the transfer-pipe, a launder and a wall over which the surface material in the receptacle passes from the receptacle 10 to the launder, which wall is located above the discharge outlet of the transfer-pipe, substantially as described.

4. Apparatus for separating minerals by flotation comprising the combination of a 15 cylindrical receptacle, a cylindrical diaphragm within the upper end of the receptacle, a transfer-pipe disposed vertically within the receptacle and having its upper discharge end located between said dia- 20 phragm and the wall of the receptacle, means for effecting the flow of the material in the receptacle upwardly through the transfer-pipe, a launder and a wall over which the material passes from the recep- 25 tacle into the launder, substantially as described.

5. Apparatus for separating minerals by flotation comprising the combination of a 30 cylindrical receptacle, a cylindrical diaphragm located concentrically within the upper end of the receptacle, a plurality of transfer-pipes disposed vertically within the receptacle and having upper discharge ends located between the diaphragm and the wall 35 of the receptacle and arranged to discharge in a horizontal direction substantially parallel to the wall of the receptacle, means for effecting the flow of the material in the receptacle upwardly through the transfer- 40 pipes, a launder and a wall over which the material passes from the receptacle into the launder, substantially as described.

6. Apparatus for separating minerals by 45 flotation comprising the combination of a cylindrical receptacle, a cylindrical diaphragm located concentrically within the upper end of the receptacle, a plurality of vertically disposed transfer-pipes in the receptacle having open lower intake ends and upper discharge ends located between the diaphragm and the wall of the receptacle and provided with elongated discharge outlets directed substantially parallel to the 55 wall of the receptacle, means for effecting the flow of the material in the receptacle upwardly through the transfer-pipes, a launder, and a wall over which the material passes from the receptacle into the launder 60 which wall is located above the discharge outlets of the transfer-pipes whereby said pipes are caused to discharge below the surface of the material in the receptacle, substantially as described.

7. Apparatus for separating minerals by 65 flotation comprising the combination of a cylindrical receptacle, a cylindrical dia- phragm located concentrically within the upper end of the receptacle, means for de- 70 livering the pulp in a circumferential direc- tion into the annular space between said diaphragm and the wall of the receptacle to cause the material within said space to take a circular motion within the receptacle, a launder, a skimmer upon the wall of the 75 receptacle over which the froth on the ma- terial in the receptacle passes from the re- ceptacle into the launder and a deflector 80 extending from the diaphragm to the wall of the receptacle adjacent to said skimmer for deflecting the froth over the skimmer, substantially as described.

8. Apparatus for separating minerals by 85 flotation comprising the combination of a cylindrical receptacle, a cylindrical dia- phragm located concentrically within the upper end of the receptacle, a plurality of 90 vertically disposed transfer-pipes within the receptacle having open lower intake ends and upper discharge ends located between the diaphragm and the wall of the recep- 95 tacle, and directed substantially parallel to the wall of the receptacle, a launder into which the material passes from the receptacle and a deflector extending from the dia- phragm to the wall of the receptacle for deflecting the material in the receptacle into the launder, substantially as described.

9. Apparatus for separating minerals by 100 flotation comprising a receptacle, a launder adjacent to the receptacle into which the material passes from the receptacle, a vertically disposed transfer-pipe within the receptacle having a lower open intake end and an upper discharge end, a pipe entering the lower open end of the transfer-pipe, means 105 for supplying compressed air to said last mentioned pipe and means for supplying oil to said last mentioned pipe, substantially as 110 described.

10. Apparatus for separating minerals by 115 flotation comprising the combination of a receptacle, a launder adjacent thereto, into which the material passes from the recep- tacle, a plurality of vertically disposed transfer-pipes in the receptacle having dis- 120 charge outlets at their upper ends located below the level of the material in the recep- tacle and directed horizontally and sub- stantially parallel to the wall of the recep- tacle and means for supplying oil and com- pressed air to the lower open ends of the transfer-pipes, substantially as described.

11. Apparatus for separating minerals by 125 flotation comprising the combination of a receptacle, a cylindrical diaphragm located concentrically within the upper end of the receptacle, a launder adjacent to the recep-

- tacle into which the material passes from the receptacle, a plurality of vertically disposed transfer-pipes in the receptacle having open lower intake ends and upper discharge ends located between said diaphragm and the wall of the receptacle and provided with outlets which are directed horizontally and substantially parallel to the wall of the receptacle, said outlets being located below the level of the material in the receptacle, and means for supplying oil and compressed air to the lower open ends of the transfer-pipes, substantially as described.
12. Apparatus for separating minerals by flotation comprising the combination of a receptacle, a cylindrical diaphragm located concentrically within the upper end of the receptacle and open at its lower end, a launder, a skimmer over which the material in the receptacle passes from the receptacle to the launder, a divertor extending from the diaphragm to the wall of the receptacle adjacent to the skimmer, and means for causing circular flow of the material between the diaphragm and the wall of the receptacle, said diaphragm having a plurality of openings therethrough near its upper edge and opposite the skimmer, substantially as described.
13. Apparatus for separating metal minerals by flotation from associated gangue or rock comprising the combination of a receptacle, a plurality of vertically disposed transfer-pipes therein having lower open intake ends and upper discharge ends directed horizontally and substantially parallel to the wall of the receptacle, means for effecting the flow of the material in the receptacle upwardly through the transfer-pipes, a launder into which the froth on the material in the receptacle passes, and means for conveying the pulp material to the receptacle and delivering it into the receptacle at a substantial distance below the level of said skimmer, substantially described.
14. Apparatus for separating metal minerals by flotation from associated gangue or rock comprising the combination of a receptacle in which the pulp is agitated and a froth accumulates on the surface of the pulp, a transfer-pipe in the receptacle having a lower open intake end terminating within the receptacle at a substantial distance below the top thereof and an upper discharge end, means for effecting the flow of the material in the receptacle upwardly through the transfer-pipe and devices for determining the level of the pulp in the receptacle and for collecting the froth accumulating upon the pulp, the outlet from said pipe being below the level at which the pulp in the receptacle is held by said level-determining devices and being directed laterally so that the material issuing therefrom causes movement of the material in the receptacle in a direction to carry the froth upon the material to said collecting devices, substantially as described.
15. Apparatus for separating metal minerals by flotation from associated gangue or rock comprising the combination of a receptacle in which the pulp is agitated and in which a froth accumulates on the surface of the pulp, a vertically disposed transfer-pipe in the receptacle having an upper discharge end directed substantially horizontally and a lower open intake end terminating within the receptacle at a substantial distance below the top thereof, devices for admitting air under pressure to the lower end of the transfer-pipe to effect a flow of the pulp upwardly through the transfer-pipe and means for determining the level of the pulp in the receptacle, said transfer-pipe being of such height that its upper end is below the level of the pulp in the receptacle as determined by said means, substantially as described.
16. Apparatus for separating metal minerals by flotation from associated gangue or rock comprising the combination of a receptacle in which the pulp is agitated and in which a froth accumulates on the surface of the pulp, a plurality of vertically disposed transfer-pipes in the receptacle having upper discharge ends directed substantially horizontally and provided with elongated discharge outlets and having lower open intake ends terminating within the receptacle at a substantial distance below the top thereof, means for admitting air under pressure to the lower ends of the transfer-pipes to effect flow of the pulp upwardly through the pipes, devices for collecting the froth accumulating upon the material in the receptacle, and means for determining the level of the material in the receptacle, said transfer-pipes being of such height that their discharge outlets are below the level of the material in the receptacle as determined by said means, and said outlets being directed laterally so that the material issuing therefrom will cause movement of the material in the receptacle in a direction to carry the froth upon the material to said collecting devices, substantially as described.
17. Apparatus for separating metal minerals by flotation from associated gangue or rock comprising the combination of a receptacle in which the pulp is agitated and a froth accumulates on the surface of the pulp, a transfer-pipe in the receptacle having a lower open intake end terminating within the receptacle at a substantial distance below the top thereof and an upper discharge end, means for effecting the flow of the material in the receptacle upwardly through the transfer-pipe, and collecting devices for collecting the froth accumulating

on the surface of the pulp in the receptacle, the discharge outlet from said transfer-pipe being directed laterally so that the material issuing therefrom will cause movement of the material in the receptacle to carry the froth thereon to said collecting devices, substantially as described.

18. Apparatus for separating metal minerals by flotation from associated gangue or rock comprising the combination of a receptacle in which the pulp is agitated and a froth accumulates upon the surface of the pulp, a vertically disposed transfer-pipe in the receptacle having a lower open intake end terminating within the receptacle at a substantial distance below the top thereof and an upper discharge end, means for admitting compressed air to the lower portion

of the transfer-pipe to cause the material in the receptacle to flow upwardly through the transfer-pipe, and collecting devices for collecting the froth accumulating upon the surface of the material in the receptacle, the discharge outlet from said transfer-pipe being directed laterally so that the material issuing therefrom will cause movement of the material in the receptacle in a direction to carry the froth on the material to said collecting devices, substantially as described.

In testimony whereof I affix my signature, in presence of two witnesses.

BERNARD MacDONALD.
